UNITED STATES PATENT OFFICE

158,499

SHOWCASE

Edwin S. Pearce, Indianapolis, Ind.

Application May 15, 1947, Serial No. 139,065

Term of patent 14 years

(Cl. D80—11)

To all whom it may concern:

Be it known that I, Edwin S. Pearce, a citizen of the United States and a resident of Indianapolis, county of Marion, and State of Indiana, have invented a new, original, and ornamental Design for a Showcase, of which the following is a specification, reference being had to the accompanying drawing, forming part thereof.

In the drawing:

Fig. 1 is a perspective view of a showcase showing my new design. Fig. 2 is a fragmentary top plan view with a portion of the showcase broken away for convenience of illustration. Fig. 3 is an elevational view thereof.

The rear of the showcase is substantially plain in appearance.

The dominant features of my design reside in the portion shown in full lines.

I claim:

The ornamental design for a showcase, as shown and described.

EDWIN S. PEARCE.
